UNITED STATES PATENT OFFICE

166,573

HANDLE FOR TRAYS

Joseph A. Potchen, Grand Rapids, Mich.

Application May 8, 1950, Serial No. 9,771

Term of patent 14 years

(Cl. D44—29)

To all whom it may concern:

Be it known that I, Joseph A. Potchen, a citizen of the United States, residing in Grand Rapids, county of Kent, State of Michigan, have invented a new, original, and ornamental Design for a Handle for Trays, of which the following is a specification, reference being had to the accompanying drawing, forming a part thereof.

Figure 1 is a perspective view of a handle embodying my new design.

Figure 2 is a front elevational view of the handle shown in Figure 1.

Figure 3 is a rear elevational view of the handle shown in Figure 1.

Figure 4 is an end elevational view of the handle show in Figure 1.

The dominant features of my design reside in the portions shown in full lines.

I claim:

The ornamental design for a handle for trays, substantially as shown and described.

JOSEPH A. POTCHEN.
